UNITED STATES PATENT OFFICE.

HARRISON E. BENEDICT, OF CHICAGO, ILLINOIS, ASSIGNOR TO IRA J. WILSON, OF CHICAGO, ILLINOIS.

AUTOMATIC TABULATING OR QUADDING-OUT ATTACHMENT FOR LINOTYPE MACHINES.

Application filed December 30, 1922. Serial No. 609,822.

To all whom it may concern:

Be it known that I, HARRISON E. BENEDICT, a citizen of the United States, residing in the city of Chicago, in the county of Cook and State of Illinois, have invented certain new and useful Improvements in Automatic Tabulating or Quadding-Out Attachments for Linotype Machines, of which the following is a specification.

This invention pertains to type-composing and type-casting machines of the class adapted to cast lines of type from a mold, to the face of which is presented and aligned a series of matrices bearing the letters, figures, or other characters, which are to be used in printing. While there are on the market a number of different makes of machines for performing this work, one make of which is commercially known as the linotype machine, the word "linotype" is used herein in its generic sense as designating machines of this general class, and is not used in its commercial sense as indicating any particular make of machine, since the principles of my invention are applicable to, and may be used in connection with, any make of machine adapted to perform the functions above indicated.

Machines of this character are used extensively in composing tabulated data, such as price lists, indexes, etc., each line of which comprises printed data in the form of letters or figures at each end of the line, the intervening space between the printed ends being either filled in with leaders or left blank, as the character of the composition requires.

In composing or setting up a line of this kind on a linotype machine, the operator sets up the printed matter at the beginning of the line by striking the proper keys on the keyboard of the machine, then fills in the space between this set-up matter and the figures and numerals, which are to appear at the other end of the line, by repeatedly depressing the leader of blank quad keys on the keyboard, as the case may be, until a sufficient number of leader or blank quad matrices have been composed in the assembler, whereupon the line is finished out by operating the requisite keys to compose the desired data at the end of the line. The repeated actuation of the leader or blank quad keys not only involves considerable

manual labor, but is also a slow and laborious operation, for the reason that the operator is unable to accurately judge with his eye the number of leaders or blank quads required in the line in order to bring the printed data at the end of the line to the proper justification. The operator is therefore obliged in composing nearly every line to stop and inspect the composed line in the assembler and either manually add one or more additional leaders or quads, or remove one or more of the same from the composed line in order to prevent over-setting or under-setting the line, and to secure the proper justification of the data at the end of the line.

One of the primary purposes of my present invention is to provide an automatic attachment for linotype machines which will automatically compose in the assembler exactly the proper number of leaders or blank quads, thereby relieving the operator of the labor of manually operating these keys, and also insuring the proper justification of line, with the result that the composing of tabulated subject matter is very materially expedited and cheapened, while at the same time the operator is relieved of the tediousness and of a large proportion of the manual labor customarily involved in composing matter of this kind.

Another object of the invention is to provide an attachment which is capable of being shifted so as to compose in the line leaders or blank quads, as the printed matter requires, when the set-up is shifted from light face to bold face or italics, and vice versa. This shifting capability of the attachment renders possible the automatic composing of the requisite leaders or blank quads irrespective of whether the matrices are assembled in what is known as the auxiliary position; that is, to raise the matrices so that the lower punching will be presented to the mold for casting, or whether the matrices are assembled in the normal position.

Another feature of the invention resides in the fact that the automatic operation of the attachment may be automatically stopped at any predetermined point in the line, and provision is also made whereby the point at which the stopping will be effected may be regulated and adjusted to a fine degree of nicety.

Another feature of the invention is that the leaders or blank quads delivered to the assembler by my automatic mechanism comprise both em and en quads, which are composed in predetermined sequence, and when the automatic composition is stopped, the delivery of the em quads ceases first and the en quads last, with the result that as the point in the line where the leaders or blank quads stop is approached, the last few quads delivered will be en, thus insuring a complete and snug filling of the line without over-setting.

A further object of the invention is to provide an attachment which will be simple in construction, economical to manufacture, one which can be readily attached to a machine of the character indicated, and one which will be reliable, efficient, and durable in operation.

Other objects and advantages of this invention should be readily appreciated by those skilled in the art as the same becomes better understood by reference to the following description, when considered in connection with the accompanying drawings.

Referring to the drawings:

Fig. 1 is a fragmentary front elevation of a linotype machine with my invention attached thereto;

Fig. 2 is a plan view of my improved attachment showing its relation to the machine, the keyboard rods of which are shown in section;

Fig. 3 is a front elevation of my attachment, shown on an enlarged scale;

Fig. 4 is a sectional view on the line 4—4 of Fig. 2;

Fig. 5 is an end elevation, partially in section, looking at the left-hand end of Fig. 2;

Fig. 6 is a fragmentary view showing the shifting mechanism and its relation to the actuating levers.

Referring now to the drawings more in detail, and particularly to Fig. 1, reference character 7 indicates generally the assembler chute cover above which is the matrix magazine of a linotype machine, from which the matrices are delivered in a well known manner to the assembling elevator 8, equipped, as is customary, with a duplex rail 9 adapted to be actuated by the hand levers 11. The assembler slide 12 is mounted to travel transversely of the machine frame, the front member 13 of which is shown in Fig. 1, the slide being restored to the right by the usual restoring lever 14 actuated by the spring 15, and being fed in a step-by-step movement to the left by the usual escapement mechanism (not shown) which is actuated from the keys 16 arranged on a keyboard in the usual manner. The brake 17 engages the slide 12 under the influence of the spring 18 and is adapted to be released at the end of

the line by the lever 10 when the assembling elevator 8 is raised to allow the line of matrices to be carried to the casting position. The adjustable abutment 19, carried upon the assembler slide clamp 21, engages the trip lever 20 when a line is over-set, and warns the operator that he must remove one or more matrices from the assembler before releasing the line. The over-set line is released by pressing the trip lever 30.

All of the parts thus far described, together with the shaft 23 driven by a gear 24, which meshes with and is actuated by the usual gear train, may be of standard linotype machine construction, or of any other preferred structure, since my invention is applicable to machines generally for casting type in lines, and, as previously mentioned, is not restricted to use in connection with a linotype machine of standard construction, portions of which are shown herein for illustrative purposes only.

An attachment embodying my invention comprises a frame structure including end members 25 adapted to be secured by bolts 26 to the front member 13 of the linotype machine. In this frame there is mounted a shaft 27 provided at the right-hand end with a pulley 28 adapted to be driven by a belt 29 from a pulley 31 mounted on the shaft 23. A series of cams, eight in the present instance, shown in dotted lines in Fig. 2 and designated by reference characters 32, 33, 34, 35, 36, 37, 38, and 39, are fixed upon this shaft. The shape of these cams is best shown in Fig. 4, from which it will be observed that the cam 32 is substantially circular in contour except for a depression 41 at one point on its circumference. The other cams are all similarly shaped and are keyed to the shaft with the depression in each cam disposed substantially at an angle of ninety degrees to the preceding and following cams of the set. It may be stated at this point that the cams are divided into two sets of four each, cams 39, 35, 34, and 32 constituting one set, and cams 38, 37, 36, and 33 constituting the other set.

Actuating levers 42, corresponding in function to the usual keyboard cam yokes, the action of which is initiated by the keys of the keyboard, are pivoted on a rod 43 and extend beneath their respective cams, the rear end of each lever being engaged in a notch 44 formed in the front face of its corresponding keyboard rod 45. It should be understood that these keyboard rods constitute a part of the linotype machine and each operates its respective matrix escapement at the upper end, and at its lower end is operated by its keyboard cam yoke. These rods are normally retained in depressed position by springs 46, and an upward pull is exerted upon each lever 42 by a tractile spring 47 of greater strength than the spring

46. Each lever 42 is provided immediately beneath its cam with a cam follower or roller 48, which is normally urged into engagement with its cam by the spring 47, so that when, upon rotation of the shaft 27, the cam depression 41 is disposed immediately over the follower 48, an upward impulse will be imparted to the rod 45 by the spring 47 to release a matrix in the magazine and permit the delivery of the same to the assembler in the usual manner. Guides 49 project rearwardly from the frame of the attachment and straddle the respective rods 45 to insure the maintenance of alignment between these rods and their respective actuating levers 42. Rearwardly of the shaft 27 there is mounted in the frame of the attachment a longitudinally movable rod or shaft 51, upon which, in proximity to the respective levers 42, there are fixedly mounted eight holdout collars indicated by reference characters 52, 53, 54, 55, 56, 57, 58, and 59. The rod is normally urged toward the right, viewing Fig. 2, by an expansion spring 61 interposed between the end of the attachment frame and a block 62 fixed on the collar. Normally, the rod is held against the action of this spring in the position shown in Fig. 2 with all of the holdout collars disposed above and in alignment with their respective actuating levers 42 by a latch member 63 pivoted at 64 upon the frame and shaped at one end to drop behind a head 65 secured to the projecting end of the rod 51. When the rod is thus locked with the holdout collars holding all of the levers 42 in depressed position against the force of their respective springs 47, the cams on the shaft 27 will revolve idly since their followers 48 are held from contact with these cams. The rods 45 will therefore remain inactive unless actuated by depression of the keys on the keyboard to which these rods are connected. The movement of the rods resulting from actuation of the keys, however, will have no influence upon the attachment, since, as will be apparent from Figs. 4 and 5, the notches in the rods are of sufficient length to afford lost motion between the rods and the actuating levers 42. The latch 63 is actuated to release the rod 51 by means of a key 66 mounted in any convenient position, preferably in proximity to the keyboard, and connected to the latch by a wire or rod 67. A spring 70 (Figs. 3 and 5) normally urges the latch into locking position.

The matrix channels in the magazine, which are controlled by the keyboard rods 45 with which the actuating levers of my attachment are connected, are supplied with two-letter matrices. The matrices in four of these channels of the magazine are supplied with the regulation quads and will cast blank spaces when composed in the normal position, and, when composed in the auxiliary position, will cast leaders. The other four channels are supplied with the regulation leaders, which, when composed in the normal position, cast leaders, and in the auxiliary position cast blank spaces. The usual equipment of the linotype machines is two channels of leaders and two channels of quads; but owing to the large number of these characters required when using my attachment, it is necessary to double this number. In order to do this, it becomes necessary to remove from the magazine several rarely used characters and to replace them with extra channels of leaders and quads, the distributing combinations of which have been previously cut to run in the desired channels.

One set of matrices is used for light face composition and the other set for bold face or italic composition. It will be apparent, therefore, that the two sets are used only in alternation, and when one set is required the mechanism which releases matrices from the other set will be thrown out of operation. It is for this reason that the cams on the shaft 27 are arranged in two sets of fours, as previously mentioned, and it will be manifest, therefore, that one set of the levers 42 should be held out of operation while the other set is being operated. To accomplish this purpose, I have provided a shift mechanism comprising a shaft 68 disposed rearwardly of the rod 51 and above the levers 42, which shaft is equipped with two series of holdout teeth 69 and 71 adapted to be alternately disposed in operative position to hold a set of levers 42 in depressed position irrespective of the position of the holdout collars on the rod 51. When the shift shaft 68 is positioned as shown in Figs. 4 and 6, those actuating levers 42 which are adapted to be actuated by the cams 39, 35, 34, and 32, will be held in depressed inoperative position. The remaining set of actuating levers controlled by cams 38, 37, 36, and 33, will be rendered operative or inoperative by their respective holdout collars, depending upon the position of the rod 51. Assuming that this last mentioned set of levers controls the quads required for light face type, should the character of the set-up change to bold face or italics, the shaft 68 will be rotated through an angle of one hundred eighty degrees to bring the teeth 69 into lower position and the teeth 71 into upper position, thereby rendering the previously operative set inoperative, and the previously inoperative set operative. This rotation of the shift shaft may be effected by any suitable mechanism, but I have shown herein, for illustrative purposes, an actuating knob 73, mounted in position accessible to the operator upon a shaft 74, which is connected through bevel pinions 75 with the shaft 68.

It will be manifest, therefore, that when a

line is to be filled in with either leaders or blanks, as the character of the set-up may require, depression of the key 66 will release the rod 51, permitting it to be moved to the right by the spring 61 so as to clear the holdout collars from the path of their respective actuating levers, thereby permitting the levers of the set which is not held in inoperative depressed position by the shifting mechanism to be actuated in succession by the respective cams on the shaft 27 to thereby cause the delivery from the magazine into the assembler of the desired matrices. When the line has been filled to the desired point, the mechanism is automatically shut off by shifting the rod 51 to the left, viewing Fig. 2, until the head 65 clears the latch 63, which will thereupon drop into locking position to restrain further operation of the attachment until the key 66 is again depressed.

The mechanism by which the operation of the attachment is automatically stopped at the desired point will now be described. In the frame of the attachment there is mounted a pair of rock shafts 76 and 77, the latter of which is equipped with an upwardly projecting fork 78, straddling the rod 51 and contacting with a collar 79, loosely disposed upon the rod and urged toward the fork by an expansion spring 81 interposed between this collar and the fixed collar 52, as will be apparent from Fig. 2. A pair of links or rods 83 are fixed to the outer ends of the rock shafts 76 and 77, and these links are pivotally connected at their upper ends to a bar 84, which is supported thereby beneath and substantially in parallelism with the assembler slide 12. A smaller bar 85, notched along its upper edge, is carried in spaced relation above the bar 84 by a standard 86 at one end of the bar 84 and a head 87 at the other end. This latter bar 85 has a pin and slot sliding connection 88 with the standard 86 and a sliding connection at its other end with the head 87. An adjusting knob 89 is rotatably mounted on the head 87, and the shaft thereof is provided with worm or screw threads 91 meshing with the notches 29 in the opposed end of bar 85. By manipulation of this knob the position of bar 85 may be adjusted longitudinally with respect to bar 84.

A slide 93 is disposed between and carried by the bars 84 and 85, and is provided with a latch 94 adapted to engage in one of the notches on the upper face of bar 85, whereby the slide is locked against movement. A finger 95 projects upwardly from this slide into the path of movement of the assembler slide clamp 21 so that movement of this clamp to the left with the assembler slide will, when it contacts the finger 95, move the bar 84 bodily to the left, thereby, through the intermediary of the links 83,

rocking the shaft 77 in a counter-clockwise direction, viewing Fig. 3, to force the collar 79 to the left through the intermediary of the fork 78. The face of the bar 84 is divided by indication marks into picas, which are numbered as indicated by reference character 96, and the notches in the upper edge of bar 85 are correspondingly spaced. The operator, knowing at what point in the line the leaders or blanks delivered by this automatic mechanism should stop, sets the slide 93 in the required position over the scale 96, indicated by the pointer 97, and if the point of stoppage be not an exact pica measurement, further adjustment to compensate for the additional number of points required is taken care of by manipulating the adjustment knob 89. A pointer or indicator 98 is disposed in proximity to this knob, the periphery of which is divided by division marks 99 into point distances commensurate with the pitch of the screw 91. The adjusting mechanism controlled by the knob 89 affords, therefore, a micrometer adjustment by which the finger 95 may be accurately set to any required points between the pica adjustment which is provided by the notches in the bar 85.

The operation of my improved attachment is substantially as follows. Assuming that an index or a price list is to be composed, the operator manipulates the keyboard to set up the required data at the beginning of the line. When the point is reached where a succession of leaders or blank quads is required, the operator, after first having set the shift mechanism to deliver either leaders or blank quads, as required, depresses the key 66 to release the rod 51, which is then shifted to the right by the spring 61 to clear the holdout collars from their respective actuating levers 42. The cam followers 48 are thereupon brought into engagement with their respective cams by the springs 47, and the levers 42 of the operative set are actuated in sequence to manipulate their respective rods 45, causing the delivery of the leader or blank quad matrices, as the case may be, to the assembler. The operator having in the manner previously described set the stop finger 95 to the previously determined pica and point adjustment, the attachment continues to operate, delivering the required matrices to the assembler until the assembler slide clamp engages the stop finger 95, whereupon the rock shaft 77 begins to turn to compress the spring 81 through the instrumentality of the fork 78.

It will be observed from Fig. 2 that the holdout collars are set on the shaft 51 in slightly different relation to their respective actuating levers 42, and as soon as the spring 81, under compression, urges the rod 51 toward the left, the collar 58 which is

- farthest to the left with respect to its lever, will upon depression of this lever move over the same into its path of movement, thereby holding the lever in depressed position and 5 throwing it out of operation. As the next lever of the set determined by the position of its holdout collar is depressed, the rod 51 will move still farther to the left projecting this holdout collar above its lever 10 and throwing it out of operation in turn. The other two levers will be similarly thrown out of operation in succession until finally all four levers of the set are thrown out of operation at which time the 15 head 68 will have passed to the left of the latch 63, which will drop into operative position, thus locking all of the levers against further actuation until a subsequent depression of the key 66.
- 20 As has been previously stated, two matrix channels of each set controlled by my attachment contain em quads while the other two contain en quads, and the holdout collars are so arranged on the rod 51 that the 25 em quads will be shut off first, and the thinner en quads last, with the result that any danger of over-setting the desired stopping point in the line by the insertion of a wide em quad is obviated and the line will 30 be filled up to the required point by the thinner en quads, thus producing a tight line without danger of over-setting.
- My invention, therefore, is adapted to automatically deliver to the assembler the required 35 number of leader or blank quads to fill in the leader or blank space in the line, and the mechanism automatically stops exactly at the predetermined point in the line for which the mechanism has been set, thereby 40 insuring a tight line and obviating over-setting. When this much of the line has been composed, the remainder is finished out by manipulation of the proper keys on the keyboard to compose the required data at 45 the end of the line.
- It should be apparent that my invention relieves the operator of the manual labor of composing the leaders or blanks in the lines of tabulated matter, and also materially expedites the composition by obviating the 50 possibility of under-setting or over-setting the leaders or blanks which in ordinary practice requires considerable time of the operator to complete the leaders or the quadding out at exactly the proper point in the line.
- While I have shown and described a preferred embodiment of my invention, it should be manifest that the principles thereof should be capable of embodiment in structures differing materially from that illustrated and described, and without departing from the essence of the invention, as defined in the following claims.
- 65 I claim:
1. The combination with a linotype machine of means for automatically composing a predetermined series of matrices in the assembler, and means for automatically stopping such composition at a predetermined point in the lines said last means being manually adjustable. 70
  2. The combination with a linotype machine of means for automatically releasing a predetermined series of matrices from the machine magazine, and manually adjustable means for automatically stopping the operation of said releasing means at a predetermined adjustable point in the line. 75
  3. The combination with a linotype machine, including a series of keyboard rods, of means for automatically actuating certain of said rods in predetermined sequence, and adjustable means for automatically stopping said operation at a predetermined point in the line. 80
  4. The combination with a linotype machine, including a series of keyboard rods, of means for automatically actuating certain of said rods, manually operable means for initiating the operation of said automatic means, and manually adjustable means for automatically stopping the operation of said automatic means at a predetermined point in the line. 90
  5. An attachment for linotype machines comprising means for causing a line being set up in a linotype machine to be automatically filled to a predetermined point by predetermined matrices, and manually operable mechanism for initiating the operation of said automatic means. 95
  6. An attachment for linotype machines comprising means for automatically operating the assembling mechanism of a linotype machine to cause the assembly in the line of predetermined matrices, manually operable mechanism for starting said automatic operation, and means for automatically stopping said automatic operation at a predetermined point in the line. 100
  7. An attachment for linotype machines comprising means for operating in succession a plurality of keyboard rods, and means adapted to be actuated by manipulation of the assembler slide for stopping the actuation of said rods when said assembler slide reaches a predetermined position. 115
  8. An attachment for linotype machines comprising means for automatically actuating in succession a plurality of keyboard rods, manually controlled means for starting the operation of said automatic means, an adjustable stop finger adapted to be actuated by movement of the assembler slide, and means operable by said finger for stopping the operation of said automatic means when said slide reaches a predetermined position. 120
  9. An attachment for linotype machines 130

comprising a plurality of continually operating cams, a keyboard rod actuating lever for each cam, holdout mechanism for rendering said levers inoperative, manually operable means for actuating said holdout mechanism to render said levers operative, and automatic means controlled by movement of the assembler slide for actuating said holdout mechanism to automatically

10 throw said levers out of operation.

11. In an attachment for linotype machines the combination of a plurality of constantly operating cams, a keyboard rod actuating lever for each of said cams, a 15 holdout rod disposed in proximity to said levers, holdout collars mounted on said rod in position to engage their respective levers and hold the same in inoperative position, a spring for normally urging said rod into 20 inoperative position, means controlled by movement of the assembler slide of the machine for moving said rod into operative position against the force of said spring to thereby render said levers inoperative, and 25 a manually controlled latch for locking said holdout mechanism in operative position.

12. In an attachment for linotype machines the combination of a plurality of keyboard rod actuating levers, cams for actuating said levers, and means controlled by 30 the position of the assembler slide for automatically throwing said levers out of operation in predetermined succession.

13. In an attachment for linotype machines the combination of a plurality of keyboard rod actuating levers, cams for actuating the same, automatic means controlled by movement of the assembler slide for throwing 35 said levers out of operation in predetermined sequence, and manually controlled means for rendering said levers operative.

14. In an attachment for linotype machines the combination of a series of keyboard rod actuating levers arranged in sets, 40 means whereby one or another of said sets may be rendered inoperative, lever actuating means, manually controlled means for initiating the operation of the operative set, and automatic means controlled by movement of the assembler slide for rendering

the levers of said operative set inoperative in predetermined succession when a predetermined point in the line is reached.

15. In an attachment for linotype machines the combination of a series of keyboard rod actuating levers arranged in sets, 45 manually controlled means for rendering any set inoperative at will, automatic means, including a stop finger adjustably disposed in the path of an element carried by the assembler slide, for rendering the levers of the operative set out of operation.

16. In an attachment for linotype machines the combination of a series of keyboard rod actuating levers arranged in sets, shift mechanism for holding the levers of a predetermined set out of operation, automatic means, including an adjustable stop finger adapted to be actuated by movement of the assembler slide, for throwing the levers of the operative set out of operation in predetermined sequence, and manually controlled means for throwing the levers of the 55 70 75 inoperative set into operation.

17. In an attachment for linotype machines the combination of a plurality of keyboard rod actuating levers, means for automatically actuating the same, and means for automatically throwing said levers out of operation, said last mentioned means comprising a stop finger adapted to be engaged by an element of the assembler slide of the 80 machine, an adjustable slide upon which said finger is carried, a pair of relatively adjustable bars between which said slide is mounted, one of said bars being provided with a pica scale and the other bar being 85 provided with notches correspondingly spaced, means for effecting a point adjustment of said last mentioned bar, a rock shaft adapted to be actuated upon movement of said bars through the intermediary of 90 said finger and means controlled by said rock shaft for throwing said fingers out of operation in predetermined sequence.

HARRISON E. BENEDICT.
